DESIGN FOR A TOY MISSILE OR SIMILAR ARTICLE

Albert G. Grier, Katonah, and Frederick M. Schubert, Hollis, N. Y.

Application April 10, 1941, Serial No. 100,308

Term of patent 3½ years

To all whom it may concern:

Be it known that we, Albert G. Grier and Frederick M. Schubert, both citizens of the United States, residing respectively at Katonah, in the county of Westchester and State of New York, and at Hollis, in the county of Queens and State of New York, have invented a new, original, and ornamental Design for a Toy Missile or Similar Article, of which the following is a specification, reference being had to the accompanying drawing, forming part thereof.

Fig. 1 is a side elevational view of a toy missile or similar article, showing my new design.

Fig. 2 is a rear end view thereof.

Fig. 3 is a front end view thereof.

We claim:

The ornamental design for a toy missile or similar article, substantially as shown.

ALBERT G. GRIER.
FREDERICK M. SCHUBERT.
